[57] ABSTRACT

A tubular, double ended electric incandescent lamp has one or more improved support members intermediate the ends of a coiled lamp filament to support the filament from the lamp envelope walls and to maintain the filament at about the axis of the lamp envelope. Each support member comprises a plurality of inter-twisted wires, each of which partially encircles the filament. The ends of the inter-twisted wires bear against the lamp envelope radially.

FIG. 7

TUBULAR INCANDESCENT LAMP HAVING IMPROVED FILAMENT SUPPORT

BACKGROUND OF THE INVENTION

1. Field of the Invention

This invention relates generally to tubular electric incandescent lamps having an axially extending coiled filament and particularly to intermediate filament supports in such lamps.

2. Description of the Prior Art

Intermediate filament supports for lamps of the type to which this invention relates generally comprise two types of supports, disc spacers and wire ring supports. Examples of the former are shown in U. S. Pat. Nos. 2,813,993, 2,830,217, 2,910,605, 2,945,978, 2,980,820 and 3,160,777. Examples of the latter are shown in U. S. Pat. Nos. 1,125,121, 2,342,044, 2,864,025, 2,883,571, 3,132,278, 3,160,454, 3,168,670, 3,194,999, 3,195,000, 3,225,247, 3,240,975 and 3,364,376.

Disadvantages of the wire ring supports are a cooling effect caused by the wire knot required to lock the support to the filament and the shading of the filament by the wire that spirals out to the envelope. In the case of the disc support, any deviation from perpendicularity to the filament will cause shading. Moreover, some filaments consist of two or more wires wound in parallel. Fastening disc supports to this type of filament is difficult and unreliable.

When incandescent lamps are used in photocopy equipment, the cooling effect on the lamp filament or the shading effect of spacers produces uneven distribution of lamp radiation on the surface exposed.

This uneven distribution is not desirable, but when a lamp is mounted close to the exposed surface or when a reflector is used to concentrate the lamp output on the exposed surface, uneven distribution becomes unacceptable.

It is an object of this invention to provide a filament support which substantially reduces uneven distribution of lamp radiation.

SUMMARY OF THE INVENTION

A lamp in accordance with this invention comprises a tubular envelope having a helically coiled wire filament extending axially therein. The filament is supported intermediate its ends by one or more improved support members. Each support member comprises a plurality of intertwined wires, each of which partially encircles the filament in such a manner that the filament is totally securely encircled by the plurality of wires. The intertwined legs of said wires extend radially away from the filament with their ends bearing against the envelope walls. Preferably there are three such intertwined legs, forming a wye shape, which substantially prevent any radial movement of the filament within the envelope.

The diameter of each wire of the support member is greater than the space between turns of the coiled filament in order to provide a wedging effect of said wire in said space. However, said diameter should not exceed the sum of said space between turns plus about $1\frac{1}{2}$ filament wire diameters in order to prevent any support wire from shorting out more than two turns of the filament.

BRIEF DESCRIPTION OF THE DRAWING

FIG. 1 is an elevational view of a lamp in accordance with this invention.

FIG. 2 is a cross-sectional view thereof, showing the shape of a support member.

FIGS. 3 to 7 show various stages in the formation of one embodiment of a support member in accordance with this invention.

DESCRIPTION OF THE PREFERRED EMBODIMENT

As shown in FIG. 1, a lamp in accordance with this invention comprises a tubular glass envelope 1 having press seals 2 at each end thereof. Axially disposed within envelope 1 is a coiled filament 3 connected at its ends to molybdenum ribbons 4 which are embedded within press seals 2. External lead-in wires 5 are connected to ribbons 4 and permit electrical energization of the lamp by connection to a suitable electrical power source.

Supporting filaments 3 are one or more intermediate support members 6, each comprising a plurality of intertwined wires. Each support member 6 supports filament 3 axially within envelope 1, the ends of the intertwined wires comprising support member 6 bearing radially against the inner wall of envelope 1, as shown in FIG. 2.

In one example of a lamp in accordance with this invention, a 1,350 watt, 115 volt, T2½ type, the lamp had an overall length of 13 inches and an effective filament length of 10 inches. Filament 3 had a diameter of 46 mils and was wound from two 10 mil tungsten wires in parallel on a 26 mil mandrel at 44 turns per inch. The space between turns was about 3 mils.

Twelve support members 6 were used to position and support filament 3 within envelope 1, the support members being spaced about nine-tenth inch apart. Each support member 6 consisted of three 10 mil tantalum wires and was made as shown in FIGS. 3 to 7. First, two of the wires, A and B, were bent to angles of about 120° and placed on filament 3, somewhat opposite each other as shown in FIG. 3. The wires were placed in the space between turns of the filament and partially wedged therein. One leg of wire A was then intertwined with the leg of wire B that extended in the same general direction, until said legs were substantially entirely intertwined together, as shown in FIG. 4. Next, the third wire, wire C, was similarly bent and placed against filament 3 so that its legs extended in the same general direction as the untwisted legs of wires A and B respectively, as shown in FIG. 5. One leg of wire C was then intertwined with wire B, FIG. 6, and the other leg was then intertwined with wire A to form a wye shaped support as shown in FIG. 7. The intertwined legs of the wye support were then cut off at a distance of 85 mils from the filament surface which permitted filament 3, with support members 6 thereon, to be inserted into envelope 1 during lamp manufacture, as shown in FIG. 2. However, the length of the intertwined legs of support member 6 was sufficient to prevent substantially any radial movement of filament 3 within envelope 1 throughout the normal operating life of the lamp.

We claim:

1. A double ended electric incandescent lamp comprising: a tubular envelope having press seals at its

ends; a helically coiled wire filament longitudinally disposed within said envelope and electrically connected to lead-in wires extending externally from said press seals; and intermediate wye shaped support members axially supporting said filament within said envelope, said support members comprising a plurality of intertwined wires, each wire partially encircling said filament so that said plurality completely encircles and secures said filament, each of said intertwined wires being partially wedged in the space between turns of 10

said helically coiled filaments, the ends of said intertwined wires bearing radially against said envelope.

2. The lamp of claim 1 wherein the diameter of each of said intertwined wires is greater than the space between turns of said helically coiled filament.

3. The lamp of claim 2 wherein the diameter of each of said intertwined wires is less than the sum of said space between turns plus $1\frac{1}{2}$ filament wire diameters.
